EXPLOSIVE CARTRIDGE AND METHOD OF
MAKING THE SAME

Don B. McCloud, Carbondale, Ill.

Application June 9, 1934, Serial No. 729,740

3 Claims. (Cl. 102—6)

My invention relates to improvements in liquid oxygen explosive cartridges and method of making the same, and my main objects are to provide a device of the character described which will have considerably greater explosive force than previous like cartridges, increase the quantity of explosive that can be loaded in a blast hole of given diameter and at the same time decrease the hazard that attends the use of liquid oxygen explosive.

Liquid oxygen explosive is made by saturating carbonaceous materials with liquid oxygen. The first cartridges used were merely cloth bags of tubular shape filled with carbonaceous materials such as lampblacks, carbon blacks, sawdust and the like which upon saturation with liquid oxygen, absorbed enough of the latter to render the mixture highly explosive. Blasting in open pit mines and quarries is accomplished by inserting saturated cartridges in previously drilled blast holes after which the cartridges are detonated by means of blasting caps.

The principal hazard in connection with the use of liquid oxygen explosive occurs when a cartridge becomes stuck or lodged in a blast hole during a loading operation. In open pit mining it is common practice to drill blast holes to a depth of forty to sixty feet. The explosive charge must be placed at the extreme ends of such blast holes in order to obtain maximum results from the blast. The original cartridges which were merely cloth bags filled with carbonaceous materials, often became soft and flabby upon saturation with liquid oxygen and in consequence were easily distorted to such an extent that while being loaded they would lodge or stick in blast holes before reaching their proper position in the extreme ends of such holes. Practically all the fatal accidents involving liquid oxygen explosive have occurred while attempts were being made to dislodge forcibly a cartridge that had become lodged or stuck in this manner.

Some inventors have tried to overcome this difficulty by the use of perforated or slotted liners or sheaths in the construction of cartridges but while these devices have constituted an improvement over the original plain, unprotected cartridges, no sheath or liner used heretofore has been of such character that it would maintain the cartridge in true cylindrical shape. As a result, it is now standard practice to sacrifice blasting efficiency by making a considerable allowance for cartridge distortion in selecting the size of cartridges to be used in blast holes of a given diameter. For example, where blast holes

of $6\frac{1}{4}$ inches diameter are drilled, the liquid oxygen explosive cartridges with which such holes are loaded have a normal, true diameter of only 4.7 inches. When such cartridges become flattened or otherwise distorted in handling so that their respective cross sections are elliptical rather than circular in shape, the difference between their normal diameter and the diameter of the blast holes is usually sufficient to provide enough clearance to allow such distorted cartridges to be loaded without sticking or lodging.

My invention relates to a cartridge that will maintain a true cylindrical shape without distortion and due to this characteristic, cartridges of this type having a diameter of 5.7 inches can be loaded in $6\frac{1}{4}$ inches diameter blast holes without danger of such cartridges becoming stuck or lodged. This greatly increases the quantity of explosive that can be loaded without hazard in such a blast hole of given length in comparison to past practices which in turn makes it possible to space blast holes farther apart than has ever been done successfully heretofore because the increase in the quantity of explosive makes a proportionate increase in the quantity of rock that can be shattered properly by each blast hole. This results in a considerable reduction in drilling costs, an exceedingly important item in most open pit mining operations.

In order to procure complete and quick saturation in the past it has been considered necessary to perforate or to provide openings of some sort in all sheaths or liners used to give structural strength or insulating qualities to liquid oxygen explosive cartridges. My present invention is entirely different from such devices used in the past in that no perforations, slots or other like openings are provided in the cylindrical portion of the cartridge. Such openings have reduced the effectiveness of protecting sheaths in two ways, namely, one, by reducing the strength of the sheath and thereby causing the sheath to crack or to collapse, which occurs frequently with saturated cartridges of previous types, and two, by providing openings through which evaporation of liquid may take place. Insofar as saturation of the cartridge with liquid oxygen is concerned, I have eliminated the necessity of perforations or other openings in the sheath by using in combination with my imperforate sheath, certain carbonaceous materials herein-after described which do not require liquid penetration throughout the cylindrical part of the cartridge in order to insure proper saturation.

My present invention eliminates many of the

difficulties heretofore experienced with liquid oxygen explosives by employing an imperforate sheath in combination with carbonaceous filling materials of the type hereinafter specified. I 5 secure a high degree of saturation in a manner never before employed in any liquid oxygen explosive cartridge, namely, by having the liquid oxygen ascend throughout the entire length of the cylindrical portion of the cartridge by capillary attraction and the displacement of occluded gases in the carbonaceous materials employed. The high degree of saturation will be maintained for a greater length of time because of the imperforate sheath. I eliminate the greatest hazard 10 in connection with the use of explosives of this type by construction that insures a true cylindrical shape of the cartridge at all times thereby avoiding the sort of distortion that occurs when other types of cartridges are packed tightly in 15 soaking boxes or otherwise subjected to pressures that occur in handling, which distortion is often sufficient to cause a cartridge to stick or lodge in a drill hole. At the same time, my invention makes it practical to greatly increase the quantity of explosive that can be loaded safely in a 20 blast hole of ordinary diameter.

My invention may be best understood by reference to the accompanying drawings, in which:

Figure 1 is a perspective view of one of my 30 liquid oxygen explosive cartridges.

Figure 2 is a sectional view taken substantially on the line 2—2 of Figure 1.

Figure 3 is a longitudinal detail view of the cartridge shown in Figure 1 with parts of the outer 35 protecting covering broken away so as to illustrate the sub-protecting sheath;

Figure 4 is a longitudinal sectional view of a modified form of cartridge;

Figure 5 is a sectional view taken substantially 40 on the line 5—5 of Figure 4; and

Figure 6 is a detail view of the sub-protecting sheath employed in the modified form of cartridge shown in Figure 4 and illustrates the method of manufacture of the sub-protecting sheath.

45 Referring now to Figure 1, the cartridge of my invention comprises an outer sheath like covering 10 made preferably of osnaburg, duck, canvas, or other material having characteristics similar to the materials mentioned. The covering is preferably cylindrical for most of its 50 length but has one end formed into a conical hollow portion 11 for the purpose of serving as a guide for the cartridge and for other purposes later to be disclosed. Within the covering 10 is arranged an imperforate casing member 14 preferably 55 formed into a cylindrical formation and having opposite open ends 15. The casing 14 and cover 10 are made of such dimensions so that the casing 14 will fit within the covering 10 rather snugly and the casing 14 is inserted into covering 10 until one end of the casing is positioned 60 adjacent the base of the conical end 11. The longitudinal dimension of casing 14 is considerably less than the longitudinal cylindrical dimension 65 of covering 10 and thus permits the end of covering 10 opposite the conical end 11 to be brought together in collapsed formation as shown at 12. The end 12 may be maintained in position and the desired closed condition by twisted 70 wire ties 13 after the casing 14 and conical end 11 have been filled with carbonaceous material later to be described.

75 Preferably, the casing 14 is made of a non-ferrous metal, such as copper, and is formed of twenty-two gauge material. The wire ties 13 are

likewise formed of non-ferrous metal, such as copper. Copper is employed for the above purpose because it will not emit sparks when struck by a projection or loading tool; the use of a ferrous metal might cause premature explosion of 5 the cartridge in case sparks were emitted.

After the casing 14 is placed within covering 10, the interior of the casing and the interior of the conical end 11 are filled with a carbonaceous material, preferably lamp black of colloidal fineness 16, or acetylene black of like fineness. It is not essential to employ unadulterated material of the character described to fill the entire space, but a satisfactory cartridge may be made by mixing small quantities of relatively more granular 15 carbonaceous materials with the lamp blacks and acetylene blacks described. Since these blacks are extremely light and fluffy, a cartridge 20 inches long and 5 inches in diameter is relatively light and may be handled with ease even after 20 saturation with liquid oxygen has been accomplished. I have found that it is desirable to pack or compress the blacks within the confines of the covering and casing to such an extent that one ounce of black of colloidal fineness comprises 25 cubic space of approximately $7\frac{1}{16}$ inches. After the filling and packing operation has been completed and the black extends to the end of casing 14 adjacent the open end of the covering 10, the end 12 of casing 14 may be drawn together as 30 above described and bound by the wire ties 13.

Referring now to Figure 4, a modified type of cartridge is shown and comprises mainly a covering 17 formed of material similar to the material of covering 10, heretofore described, and having a similar conical end 18 and end 19 similar to open end 12 of the form shown in Figure 1, which may be closed and bound by wire ties 20 which are similar to wire ties 13 and formed of a similar material. An imperforate casing 21, preferably of cylindrical formation, is received within the covering 17 and adapted to extend from the base of conical end 18 to a point adjacent the opposite end of covering 17.

Referring now to Figure 6, the casing 21 is preferably 45 formed of laminated chipboard, strawboard, pressboard, cardboard or material having similar characteristics. Preferably, the lower layer 23 is formed of a strip of helically wound material of the character described and upon this lower or interior layer 23 is wound a strip or layer 50 24. Strip 24 is likewise helically wound and is adapted to overlap the meeting edges of the strip 23, but the edges of the strip 24 are preferably arranged in abutting relation throughout its helical course. An outer layer or strip 25 is wound in a helical formation around the layer 24 and adapted to overlap the meeting edges of the strip 24 throughout its helical course. The various layers may be secured together by various 60 kinds of mucilaginous material and the casing thus formed is capable of withstanding considerable shocks and stresses without appreciable deformation.

Casing 21 and conical end 18 of covering 17 are 65 then filled with lamp black of colloidal fineness 26 or acetylene black of like fineness in a manner similar to the filling and packing of the material 16 in casing 14 and conical end 11. The end 19 is closed and bound in place by the copper 70 wire tie 20, heretofore described.

The cartridge is now ready for the saturating operation and the subsequent operations are carried on in identically the same manner, regardless of whether the cartridge shown in Figure 1 75

or that shown in Figure 4 is employed. The cartridge is placed in a heat insulated tank with the conical end of the cartridge extending toward the base of the tank preferably the gathered end 5 of the bag serving as a handle by means of which the cartridge may be grasped. Liquid oxygen is then poured into the tank in sufficient quantities so that the conical end is entirely submerged at all times during the saturation period. Since the 10 temperature of the liquid oxygen is approximately 182 degrees below zero Fahrenheit it causes a shrinkage of the occluded gases contained in the lamp black or acetylene black and as these 15 occluded gases contract, the liquid oxygen is drawn into the interior of the casing in a manner similar to that in which air rushes into a broken vacuum. As the liquid oxygen is adsorbed by the lamp black or acetylene black employed, it successively cools the occluded gases occurring in the 20 upper portions of the black employed and successively the liquid oxygen is adsorbed until the entire mass of black is saturated. An effective explosive is formed if the carbonaceous material bears a relation of 1. to 2.6 by weight of liquid 25 oxygen, but since evaporation of liquid oxygen is very rapid it is always advisable, if possible, to achieve a degree of saturation in which the carbonaceous material will bear a relation of 1. to 3. or more, to the liquid oxygen by weight. This 30 surplus of liquid oxygen maintains the effectiveness of the cartridge during the necessary loading time, which ordinarily should not consume more than thirty to forty five minutes.

It can be seen that the imperforate inner casing presents a structural covering having much greater resistance to deformation than a casing of similar material with slots or various kinds of perforations therein. Likewise, the imperforate casing prevents evaporation of liquid oxygen 35 to a great extent and keeps the cartridge in an effectively saturated condition for a longer period of time. Because of this factor the sphere of usefulness of liquid oxygen explosive is considerably broadened.

45 The employment of carbonaceous materials of colloidal fineness and particularly, lamp blacks and acetylene blacks in a cartridge that will maintain a true cylindrical shape at all times, furnishes a cartridge of a degree of effectiveness 50 heretofore unknown in the liquid oxygen explosive art. This degree of effectiveness is attained without a sacrifice of safety because of the additional strength and rigidity of the protecting casing employed beneath the outer covering. The in-

crease in effectiveness likewise broadens the field of usefulness of liquid oxygen explosive and makes it possible for the many admitted advantages of this type of explosive to be utilized for other similar purposes.

An imperforate sheath of non-ferrous or non-metallic material may be employed in place of the preformed tubular casing herein described and a small overlap of edges of the material would provide a complete cylindrical protecting covering 5 for the incased carbonaceous material. The other steps in making the cartridges would be identical.

While I have shown and described my preferred form of construction and have disclosed my preferred materials and method of manufacture, I 15 do not wish to be limited to the details herein shown and described but wish to avail myself of all variations of structure, materials and method coming within the scope of the appended claims.

Having thus described my invention, what I 20 claim as new and desire to secure by Letters Patent is:

1. A liquid oxygen cartridge comprising an open end casing of material impervious to liquid oxygen, an outer cloth covering for said casing, 25 a filler of carbonaceous material in said casing and partially extruded therefrom into said covering at one end, and means for closing said covering to retain the carbonaceous material within said casing and covering after same has been 30 filled, said carbonaceous material adapted to be saturated with liquid oxygen through said extruded end.

2. A liquid oxygen cartridge comprising an open end casing of liquid oxygen impervious material, a filler of carbonaceous material of colloidal fineness in said casing and extending out beyond one end thereof, a cloth covering for said casing and carbonaceous material, and closure means for said casing and covering at one end, 35 40 said cartridge adapted to be saturated with liquid oxygen at the opposite end.

3. A liquid oxygen cartridge comprising an open end casing of material impervious to liquid oxygen, a filler of carbonaceous material in said casing, 45 a textile envelope adapted to secure a quantity of said carbonaceous material therein beyond an end of said casing, and means to close said envelope after same has been filled, said envelope adapted for saturation of carbonaceous 50 material with liquid oxygen through said extended end portion after said filling.

DON B. McCLOUD.
